PUMP CONTROL VALVE

Erich, Henkel, Calumet City, Ill., assignor to The
Superheater Company, New York, N. Y.

Application February 26, 1941, Serial No. 380,655

4 Claims. (Cl. 103—16)

The present invention relates to pump control devices and particularly to improvements in control valves for preventing overspeeding of a centrifugal pump.

Centrifugal pumps such as are employed for feeding water to locomotive boilers are provided with mechanical governors arranged to shut off steam to the turbine driving the pump in the event that conditions arise which cause it to overspeed. However, in the operation of feed water pumps on locomotives, conditions may arise causing the governor to trip frequently, thus causing repeated operation and wear of the tripping mechanism. For the purpose of avoiding undue wear of tripping mechanisms of pumps of this type in order that they may be in good condition to become effective should dangerous overspeeding occur, various types of control valves automatically responsive to conditions, other than speed, which serve to indicate the state of operation of the pump have been devised. Improved valves of this type are disclosed in the copending application filed in the name of Joseph F. Griffin on February 23, 1940, under serial No. 320,329. The present invention contemplates a further improvement in control valves of this type. The improvement is particularly designed to prevent overspeeding of the pump as a result of supplying steam in excessive amounts or at excessively high pressures at times when there is no load on the pump, as for example when both the suction and delivery lines of the pump are dry.

The invention will be best understood upon consideration of the following detailed description of an illustrative embodiment thereof when read in conjunction with the accompanying drawing in which:

Figure 1 is a diagrammatic view of parts of a pump system embodying the control valve of the present invention; and

Figure 2 is an enlarged view partly in section to show the detailed construction of the control valves that prevent overspeeding of the pump.

In Figure 1 the numeral 10 designates a turbine driven centrifugal pump drawing water as from a locomotive tender through a suction line 11 and supplying it to the boiler through a pipe 12 leading to the boiler check valve. The pump 10 is operated by steam supplied through a pipe 14 subject to the control of a throttle valve 15 and a hydraulic responsive control valve which is designated as a whole by the numeral 16.

The control valve 16 comprises a housing 20

having therein a valve member 21 provided with a pair of valve disks 22 connected to a stem 23 that projects through the bottom 24 of the housing. Mounted on the underside of the valve 5 casing 20 concentric with valve stem 23 is a piston cylinder 30 formed with a chamber 31. In cylinder 30 is a piston 60 subjected at its upper end to the pressure of steam reaching the chamber 31 from the valve inlet 26 through a passage 33 of a relatively small area. The piston 60 is also subjected on its under side to the delivery pressure of pump 10 conveyed to the chamber 35 through a pipe 36 connected to the water delivery line 12, as shown in Fig. 1. 10 A vent 63 in the wall of the upper chamber 31 is so located that when valve 21 is closed, steam is bled from the chamber 31 and its pressure cannot act to prevent the opening of the valve by pump delivery pressure acting on the under side of piston 60. As piston 60 ascends to open valve 21, it obscures the vent port 63 so that the steam pressure is built up in the chamber at the upper face of the piston and acts if delivery pressure fails to automatically close valve 21. A by-pass 25 is connected to the steam line 14 adjacent the inlet 26 and outlet 27 of valve 16. Chokes in the by-pass permit only a limited amount of steam for starting the pump slowly to flow to the turbine of pump 10 whenever the throttle valve 15 is opened although the control valve 21 may still be closed.

The hydraulic control valve described above is identical with one of the forms described in the Griffin application in all respects except 35 that herein the pipe 25 by-passes the valve 16 whereas in the application a small orifice is formed in the wall that separates the inlet 26 and outlet 27 of the valve. The reference numerals used above correspond to those employed in the patent.

In accordance with the present invention a pressure relief valve designated as a whole by the numeral 10 is connected into the by-pass 25, as for example between the chokes 16 and 45 72. This relief valve prevents the pressure of steam flowing through the by-pass to the pump exceeding a predetermined value upon the opening of throttle valve 15, regardless of the degree of opening of the latter. The relief valve 10 comprises a valve disk 73 held against its seat by a spring 74 to close off the vent line 75 from the by-pass 25, the spring being selected and arranged to hold the valve 73 closed until a predetermined steam pressure is reached in the by-pass 25. When valve 10 opens, steam is vented

off through a line 76 so as to relieve the pressure in the by-pass. The valve 73 is operatively connected to a piston 77 subjected to the pump delivery pressure through a conduit 78. A spring 80 is arranged to oppose delivery pressure acting on piston 77 so that the valve 73 does not close, if it has opened, until a predetermined pump delivery pressure is attained.

When the throttle valve 15 is opened steam flows through the by-pass 25 and the chokes 71 and 72 tend to limit the pressure and amount of steam to value suitable for starting of the pump and operating it slowly. However, if the pump happened to be without load as a result, for example, of both its suction and delivery lines being dry, even a relatively small quantity of steam passing through the by-pass might cause it to overspeed. To avoid this, the relief valve 10 acts whenever the pressure in the by-pass 25 exceeds a predetermined selected safe value to vent part of the steam from the by-pass through the line 76 so that under all conditions a safe pressure is maintained at the inlet of the turbine that drives the pump. If, however, the pump is operating under normal conditions it slowly builds up water delivery pressure. When a predetermined delivery pressure is reached it acts on piston 77 to move it downwardly so as to close the valve 73, or hold it to its seat if it has not opened. Closing of the relief valve permits the steam pressure reaching the pump through the by-pass to increase, thus speeding up the pump. When the pump operates at a predetermined water delivery pressure, which need not necessarily be the same as that controlling the valve 73, the delivery pressure communicated to the under side of piston 60 acts to raise the latter. This results in opening the control valve 21 so that the pump may speed up and further increase the delivery pressure to the value required to feed the boiler. As valve 21 opens piston 60 obscures the vent 63 so that steam pressure corresponding to that at the inlet 26 of the valve 21 is built up in the chamber 31. Thereafter if the water delivery pressure should fall below said predetermined value, the pressure of steam in the chamber 31 acts on the upper face of piston 60 to close the valve 21, thus slowing down the pump to the rate of operation permitted by the amount of steam flowing through the by-pass 25.

What I claim is:

1. In a pump control system having a conduit for supplying steam to the pump, a control valve in said conduit arranged to open when the pump delivery pressure reaches a predetermined value and to close when said pressure falls below said value, and a by-pass around said control valve for permitting a limited amount of steam to flow to said pump for operating the latter slowly when said control valve is closed; a relief valve associated with said by-pass for preventing the pressure of steam flowing through said by-pass to said pump exceeding a predetermined value; and means responsive to a predetermined pump

65 delivery pressure operatively connected to said relief valve so as to render it ineffective when said last delivery pressure is attained.

2. In a pump control system having first a 5 throttle valve and then a control valve in series in a conduit supplying steam to the pump, a restricted by-pass around said control valve for passing a limited amount of steam to the pump when said throttle valve is open though said 10 control valve is closed, means responsive to a predetermined pump delivery pressure operative to open said control valve, and means for closing said control valve when the pump delivery pressure falls below said predetermined value; a relief valve associated with said by-pass for preventing the pressure of steam flowing therethrough to the pump exceeding a predetermined value on opening of said throttle valve to start the pump; and means operatively connected to said relief valve and responsive to a predetermined delivery pressure for rendering said relief valve ineffective when said last pressure is attained.

25 3. In a pump control system having a control valve in a conduit supplying steam to the pump, a by-pass around said control valve for passing a limited amount of steam to the pump when said throttle valve is open though said control valve is closed, means responsive to a predetermined 30 pump delivery pressure operative to open said control valve, and means for closing said control valve when the pump delivery pressure falls below said predetermined value; a relief valve associated with said by-pass for preventing the pressure of steam flowing therethrough exceeding a predetermined value on opening of said 35 throttle valve to start the pump; and means operatively connected to said relief valve and responsive to a predetermined delivery pressure for rendering said relief valve ineffective when said pressure is attained.

40 4. In a pump control system having first a throttle valve and then a control valve in series in a conduit supplying steam to the pump; a by-pass comprising a pipe connected to said conduit at both sides of said control valve; means in said by-pass for restricting the amount of steam flowing through the latter to said pump so as to permit only a relatively small amount of fluid to flow to said pump when said control valve is closed; means responsive to a predetermined 45 pump delivery pressure operative to open said control valve; and means for closing said control valve when the pump delivery pressure falls below said predetermined value; a pressure 50 relief valve connected to said by-pass for maintaining steam pressure therein below a predetermined value; and means responsive to a predetermined delivery pressure of the pump operatively connected to said relief valve so as to render it ineffective when said delivery pressure is attained for permitting increase of the pressure of actuating fluid flowing through said by-pass to said pump.

ERICH HENKEL.
